UNITED STATES PATENT OFFICE.

ALFRED F. MORRELL, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

MULTIPLIER.

Application filed November 25, 1924. Serial No. 752,221.

This invention relates to a multiplier for use in controlling the movements of the shifting shuttle boxes for a drop box loom or for other similar purposes. In such 5 looms it is customary to provide a multiplying chain which will permit the main pattern chain to remain at rest for a predetermined number of picks.

The number of links between the risers in 10 the multiplying chain must usually correspond to the smallest number of repeats for which the multiplying chain is to be used. For each renewed operation of the multiplier, an additional link in the main pattern 15 chain is required to again start the multiplier in operation.

A fabric may frequently have a design in 20 which broad and narrow bands of color occur. This limits the repeats of the single 25 chain multiplier to the small number of picks in the narrow bands, and requires a large number of renewed operations of the multiplier for the wide bands, with a corresponding increase in the length of the main pattern chain.

It is the object of my invention to provide additional multiplying mechanism by 30 which such broad bands may be woven with a greatly reduced number of links in the main pattern chain. For this purpose, I provide a second or auxiliary multiplying chain having a substantially larger number of links between risers or more commonly with a single riser only in a comparatively 35 long chain.

I also provide connections by which the loom will continue in operation for the 40 minimum number of picks indicated by the auxiliary multiplier chain, regardless of the indications of the primary multiplier chain. In the preferred form the auxiliary multiplier chain acts to hold the shifting mechanism for the main chain clutch inoperative, even when released by the primary multiplier.

My invention further relates to arrangements and combinations of parts which will 45 be hereinafter described and more particularly pointed out in the appended claims.

A preferred form of the invention is 50 shown in the drawings in which

Fig. 1 is a plan view of my improved multiplier;

Fig. 2 is a rear elevation, looking in the 55 direction of the arrow 2 in Fig. 1;

Fig. 3 is a detail sectional view, taken along the line 3—3 in Fig. 1;

Fig. 4 is an end elevation, looking in the direction of the arrow 4 in Fig. 1;

Fig. 5 is a partial front elevation, looking 60 in the direction of the arrow 5 in Fig. 1;

Fig. 6 is a sectional view, taken along the axis of the multiplier shaft, and

Fig. 7 is a detail sectional elevation, taken 65 along the line 7—7 in Fig. 1.

Referring to the drawings, I have shown my improved multiplier assembled upon a frame 10 which may be rigidly secured to a loom frame 11 (Fig. 4). The main pattern chain 12 (Fig. 2) is mounted on driving 70 sprockets 13 on a sleeve 14, freely rotatable upon a shaft 15 fixed in the frame 10. A disc 16 (Fig. 2) fixed to the sleeve 14 is provided with a series of notches or recesses in its outer face, adapted to receive a lug or 75 projection 17 (Fig. 1) formed on a clutch collar 18 which in turn is slidable on a second sleeve 19. The collar 18 has an annular groove which receives a projection on the end of an arm 20 (Fig. 2) mounted on a 80 fixed pivot 21.

The sleeve 19 has a notched disc 22 at one end and a worm gear 23 at the opposite end. The gear 23 (Fig. 4) is intermittently advanced by a dwell worm 24 on an upright 85 driving shaft 25 suitably connected to any desired mechanism by which the shaft is continuously rotated. The worm gear 23 is thus intermittently advanced, carrying with it the collar 18. The main pattern chain is 90 similarly advanced when the collar 18 is moved to the right in Fig. 2 to connect the worm gear 23 to the sprockets 13.

A hand wheel 26 is secured to the upper end of the shaft 25 by which the shaft may 95 be turned to reset the pattern if desired while the loom is at rest, suitable provisions being made for disconnecting the driving mechanism from the shaft 25.

A primary multiplier chain 30 is mounted 100 upon sprockets 31 (Fig. 5) and a guide pulley 31^a (Fig. 4). The guide pulley 31^a is adjustably secured in a bracket 31^b in which it may be raised and lowered to accommodate pattern chains of different lengths.

The sprockets 31 are fast on a sleeve 32 (Fig. 6) freely rotatable upon a shaft 33 fixed in the frame 10. The driving connections for the sprockets 31 are similar to those already described and include a disc 110

34 fast on the sleeve 32 and having recesses to receive an arm or projection 35 (Fig. 5) on a clutch collar 36 slidable on a second sleeve 37 having a notched disc 38 at one end and a worm gear 39 which meshes with the intermittent worm 24 previously described and which is thus periodically advanced. The collar 36 is grooved to receive a lug 40^a (Fig. 1) projecting laterally from the lower end of a depending arm 40 pivoted on a horizontal shaft 41.

A second or auxiliary multiplying chain 45 (Figs. 5 and 6) is mounted upon sprockets 46 on a sleeve 47 having a recessed disc 48 formed at one end thereof. The sleeve 47 is freely rotatable upon the fixed shaft 33 previously described. An adjustably mounted guide pulley 49 (Fig. 4) supports the outer end of the auxiliary chain 45.

20 The sprockets 46 are intermittently advanced by a member 50 (Fig. 5) formed on a clutch collar 51 slidable on the sleeve 32 of the sprockets 31. A notched disc or plate 52 on the end of the sleeve 32 drives the arm 50 and in effect connects the sprockets 46 to the sprockets 31 for simultaneous advance movements when the clutch member 50 is in operative position. The collar 51 is grooved to receive a clutch-shifting arm 53 pivoted at 54 on a fixed bracket 55.

35 I will now describe the mechanism and connections for controlling the movements of the clutch collars 18, 36 and 51 by which the movements of the main pattern chain, the primary multiplying chain and the auxiliary multiplying chain are respectively controlled.

An arm 60 (Fig. 5) is closely pivoted on the shaft 41 previously described and is secured by a binding screw 61 to a yoke 62 (Fig. 4) which spans the arm or lever 40 previously described. The yoke 62 has a laterally projecting arm 63 (Figs. 1 and 2), the outer end of which is positioned above a projection 64 (Fig. 2) on the controlling arm 20 for the clutch collar 18. A coil spring 65 interposed between the arm 63 and the projection 64 provides a resilient actuating connection between the arm 60 and the clutch collar 18.

50 When a riser 66 (Figs. 4 and 5) on the primary multiplier chain 30 raises the arm 60 the arm 63 (Fig. 2) will be depressed and, unless otherwise prevented, will cause driving engagement of the clutch collar 18 with the disc 16 to advance the main pattern chain 12.

The arm 40 (Figs. 1 and 5) which controls the clutch collar 36 for the primary 60 multiplier chain is provided with a laterally projecting member 70 pivoted on the fixed shaft 41 and clamped to the arm 40 in desired angular relation by a clamping screw 71 (Fig. 1). At its outer end the arm 65 70 is provided with an offset end portion

72 to which is pivoted a lever 73 (Fig. 7) extending over one series of links or risers 75 of the main pattern chain 12. A spring 77 (Fig. 7) forms a resilient connection between the arm 70 and the lever 73. When a riser 75 of the main pattern chain raises the arm 70 it acts yieldingly through the spring 77 to swing the arm 40 (Fig. 5) to the left, thus connecting the clutch collar 36 to advance the primary multiplier chain 30.

The arm 53 (Fig. 5) for the clutch collar 51 associated with the auxiliary multiplier chain 45 has a laterally projecting slotted portion 80 engaged by a pin or stud 81 (Figs. 5 and 6) secured in a lug or projection 82 (Fig. 1) formed on a hub 83 pivoted on a shaft 84 fixed in an upper portion of the frame 10. The hub 83 has an arm 85 (Fig. 1) projecting therefrom and extending over a second series of risers 86 (Fig. 2) on the pattern chain 12. When a riser 86 raises the arm 85, the arm 53 (Fig. 5) is moved to the left to cause driving connection for the auxiliary multiplying chain 45.

A contact arm 90 (Figs. 1 and 5) projects laterally from a yoke 91 pivoted on the fixed shaft 84 and is raised by a riser 66 on the auxiliary multiplier chain 45. An arm 92 (Fig. 1) projects laterally from the opposite end of the yoke 91 and is provided with an adjustable contact screw 93. A locking lever 94 (Fig. 1) is pivoted at 95 on the offset outer end 96 of the lever 85 previously described. A coil spring 97 (Figs. 3 and 4) forms a resilient connection between a depending portion 98 of the offset end 96 of the lever 85 and the locking lever 94.

At its outer end, the lever 94 is provided with a depending portion 100 (Fig. 2) having a lug 101 projecting rearwardly therefrom. When the lever 85 is raised, the lug 101 is normally positioned in the path of a projection 102 (Figs. 1 and 2) on the clutch lever 20 previously described. A riser 86 on the main pattern chain 12 will thus act to render the lug 101 operative to lock the clutch collar 18 in inoperative position.

Having described the details of construction of my improved multiplier, I will now describe the operation thereof. During the ordinary operation of the loom, the regular drop box controlling levers 110 (Figs. 1 and 2) are actuated by the risers 111 on the main pattern chain 12. When, however, a short repeat of the pattern is desired, a special riser 75 is placed on the pattern chain 12 (Fig. 7) in position to cause the arm 40 (Fig. 5) to move the clutch collar 36 to engage the disc 34 and cause intermittent advance movement of the primary multiplying chain 30. Upon the first advance movement of the multiplying chain 30, a riser 66 thereon is moved away from the arm 60

(Fig. 5) and a spring 112 pulls the arm 60 downward, thus swinging the arm 20 (Fig. 2) to the left and disengaging the clutch collar 18. The main pattern chain 12 therefore 5 after remains at rest until a riser 66 on the primary multiplying chain 30 again lifts the arm 60 and engages the clutch 18 to drive the main chain 12.

In the drawings, the multiplying chain 30 10 is shown as having a riser 66 at every fifth link of the chain. Each time the multiplier is started, it will thus cause the insertion of ten picks of a single color of weft or filling before the main pattern chain is again 15 started.

When a longer repeat is desired, a riser 86 (Fig. 2) is placed on the main pattern chain 12 to engage the lever 85 which controls the auxiliary multiplier chain 45. As the lever 20 85 is lifted, it rocks the arm 53 (Fig. 5) to the left, engaging the clutch collar 51 to drive the auxiliary pattern chain 45.

As soon as this auxiliary chain 45 is started, its riser 115 (Fig. 4) is moved away 25 from the arm 90 (Fig. 5), thus leaving the arm 92 and contact screw 93 (Figs. 1 and 3) free to move upward. This permits of swinging upward movement of the arm 94 (Fig. 2) on its stud 95 under the influence 30 of the coil spring 97 (Fig. 3). The offset end 101 of the arm 94 is thus moved into the path of the lug 102 on the shifting arm 20 for the clutch 18, as indicated in Fig. 2.

While the parts are thus positioned, the 35 riser 66 on the primary multiplying chain 30 may rock the arm 60, depressing the connected arm 63 (Fig. 2) but such action will merely compress the spring 65 and cannot shift the clutch collar 18 until the riser 115 40 on the auxiliary pattern chain lifts the arm 90, thus depressing the contact screw 93 and pushing the lever 94 downward against the pressure of the spring 97 to clear the projection 102.

45 In actual operation of the device, the primary and auxiliary multiplier chains are so related that a riser 66 on the primary chain 30 will engage the arm 60 whenever the riser 115 on the auxiliary chain engages the arm 90. Thus, as soon as the arm 94 is depressed 50 so that its end portion 101 clears the lug 102, the spring 65, already compressed acts to move the arm 20 and engage the clutch 18. As soon as the main pattern chain 12 is thus 55 set in motion, the riser 86 moves from under the lever 85, thus dropping the lever 94 pivoted thereon substantially below the projection 102.

More concisely stated, a riser 75 is inserted 60 on the main pattern chain 12 whenever it is desired to start the primary multiplier chain 30 and a riser 86 is inserted in the chain 12 when a greater number of repeats is desired. Whenever the auxiliary 65 chain 45 is in operation, the primary chain

30 is not effective to start the main chain 12 until the riser 115 on the auxiliary chain 45 also comes into operative position.

The auxiliary chain 45 may have any desired number of links and is used for long 70 repeats containing, for instance, forty picks. If fifty picks are desired, both the primary chain 30 and the auxiliary chain 45 are started for one series of forty picks and the primary chain 30 is then again started for 75 an additional series of ten picks. It is desirable that the number of links per riser in the primary chain 30 should be an exact divisor of the number of links in the auxiliary chain 45.

Having thus described my invention and the advantages thereof, I do not wish to be limited to the details herein disclosed otherwise than as set forth in the claims, but what I claim is:—

1. In a multiplier, a main pattern chain, a primary multiplier chain, an auxiliary multiplier chain, means controlled by the main pattern chain effective to start said primary and said auxiliary chains, means 90 actuated by said primary chain for starting said main chain, and means controlled by said auxiliary chain effective to render said last named means inoperative.

2. In a multiplier, a main pattern chain, 95 a primary multiplier chain, an auxiliary multiplier chain, means controlled by said main chain effective to start said primary chain, additional means controlled by said main chain effective to start said auxiliary 100 chain, and devices jointly controlled by said primary and auxiliary chains effective to hold said main chain inoperative for a selected number of picks.

3. In a multiplier, a main pattern chain, a 105 primary multiplier chain, an auxiliary multiplier chain, regularly actuating driving mechanism, means controlled by said main chain effective to connect said primary chain to said driving mechanism, additional means 110 controlled by said main chain effective to connect said auxiliary chain to said primary chain, and means jointly controlled by said primary and auxiliary chains effective to connect said main chain to said driving 115 mechanism.

4. In a multiplier, a main pattern chain, a primary multiplier chain, an auxiliary multiplier chain, regularly actuating driving mechanism, and pattern-controlled 120 means for selectively connecting each of said respective chains to said driving mechanism and for disconnecting the same, said primary chain being operative with or separate from said auxiliary chain, but said auxiliary 125 chain operating only in unison with said primary chain.

5. In a multiplier driving mechanism, a main pattern chain, a primary multiplier chain, an auxiliary multiplier chain, connec- 130

tions through which said main chain is effective to connect said primary chain or said auxiliary chain and said primary chain to the driving mechanism, and means including a yielding connection through which said primary chain is operable to connect said main chain to said driving mechanism.

6. In a multiplier, a main pattern chain, a primary multiplier chain, an auxiliary multiplier chain, driving mechanism for said primary chain controlled by said main chain, driving mechanism for said auxiliary chain controlled by said main chain, and driving mechanism for said main chain yieldingly controlled by said primary chain and operable only when released by said auxiliary chain.

7. In a multiplier, a main pattern chain, a primary multiplier chain, an auxiliary multiplier chain, driving mechanism for said primary chain controlled by said main chain, driving mechanism for said auxiliary chain controlled by said main chain, driving mechanism for said main chain yieldingly controlled by said primary chain, and a locking device for said main chain driving mechanism effective in operative position to hold said main chain driving mechanism inoperative, said locking device being movable from locking position by said auxiliary chain.

8. In a multiplier, a main pattern chain, a primary multiplier chain, an auxiliary multiplier chain, clutch mechanism for said primary chain controlled by said main chain, clutch mechanism for said auxiliary chain controlled by said main chain and operable with said primary chain, and clutch mech-

anism for said main chain jointly controlled by said primary and said auxiliary chains.

9. In a multiplier, a main pattern chain, a primary multiplier chain, an auxiliary multiplier chain, a main clutch mechanism, a locking device for said main clutch mechanism, connections from said primary chain effective to render said main clutch mechanism operative but said connections being rendered inoperative by said locking device, and means operable by said auxiliary chain for releasing said main clutch mechanism from said locking device.

10. In a multiplier, a main pattern chain, a primary multiplier chain, an auxiliary multiplier chain, a main clutch mechanism controlled by said primary chain, a locking arm yieldingly positioned to prevent operable re-engagement of said main clutch mechanism after said main clutch mechanism is disengaged, and means operable by said auxiliary chain for moving said locking arm to inoperative position.

11. In a multiplier, driving mechanism, a main pattern chain, a primary multiplier chain, an auxiliary multiplier chain, regularly actuated driving mechanism, and connections through which said main chain is effective to connect said primary chain or said auxiliary chain and said primary chain to said driving mechanism, the number of links for each riser of said auxiliary chain being an exact multiple of the number of links for each riser of said primary chain.

In testimony whereof I have hereunto affixed my signature.

ALFRED F. MORRELL.
